UNITED STATES PATENT OFFICE

GEORGE W. MILLER, OF GLEN ELLYN, ILLINOIS

HAIR WAVING APPARATUS

Application filed August 7, 1931. Serial No. 555,721.

My invention relates to apparatus for waving hair by means of improved appliances and relates particularly to the so-called crouquinole type of permanent wave in which 5 a tuft of hair is wound in a relatively straight coil upon a rod, starting at a given point and working toward the scalp so that the succeeding turns are enlarged due to the increased diameters thereby increasing the 10 length of the corresponding waves. In such a system a clamp holds the tuft of hair in position and the coil rod upon which the hair is wound is supported by the clamping member. Next a prepared pad is placed over the 15 coil of hair and heaters are applied and the hair steamed.

An object of my invention is to provide a hair waving apparatus which is simple in construction and at the same time a great improvement over the apparatus in use at present.

The use of my apparatus permits the operator to be in full control of his means to produce a good wave through the elimination 25 of uncertain stretching of the hair in turning in the uneven ends, greatly reducing the time required for the operation and eliminating unnecessary pulling of the scalp which is painful.

Another object of my invention is to produce a device which produces waves very close to the scalp. In the devices now in use only a slight curved impression, which disappears in a few days, is produced near the 30 scalp and the first wave is about two inches away from the scalp. As this distance represents a few months' growth of the hair it will readily be seen that by the use of the device of my invention it will be unnecessary to repeat the operation at such frequent intervals as is necessary with the devices at present in use.

A further object of my invention is to provide means to prevent the injuring of the fine hair structure due to oversteaming by employing a so-called apron member formed of canvas or other suitable material which is adapted to be wound in with the hair as it is rolled upon the coil rod and which retains the moisture during the steaming process a

greater length of time than is at present attainable.

Another feature of my invention is the provision of a pair of flexible metal members on the usual pad for holding the pad in position on the coil of hair.

Other features and objects of my invention will appear from time to time as the description of my invention progresses.

My invention will be better understood by reference to the accompanying drawing in which like reference characters in the different views indicate like parts and in which:

Fig. 1 is a plan view of a clamping member forming part of my invention.

Fig. 2 is a sectional view along the line 2—2 of Fig. 1.

Fig. 3 is a left end view of Fig. 1,

Fig. 4 is a right end view of Fig. 1,

Fig. 5 shows the clamping member in its open position,

Fig. 6 shows a coil rod of my invention, and

Fig. 7 shows the pad with the flexible members thereon.

The present invention will be best understood from a consideration of the following detailed description taken in connection with the accompanying drawing forming a part of this specification, with the understanding, however, that the invention is not confined to any strict conformity with the showing of the drawing but may be changed or modified so long as such changes and modifications mark no material departure from the salient features of the invention as expressed in the appended claims.

Referring more particularly to Fig. 1 which discloses the clamping member CM which consists of an upper jaw 1 and a lower jaw 2; an extension 3 is integrally formed with the lower jaw 2 and pivot pin 4 extends therethrough and through the upper jaw 1 which allows jaws 1 and 2 to be opened as shown in Fig. 5. A fastening member 5 is provided to hold the jaws 1 and 2 in their closed position and this fastening member 5 comprises an arm 6 which is pivotally secured to a plate 7 secured in any suitable manner to the upper jaw 1. The arm 6 has

an extension 8 and an offset portion 9 which has its end 10 bent back upon itself to form a bearing for the extended portion of a wing nut 11 which has secured thereon a cam member 12 which engages a member 13 integrally formed with a portion of the lower jaw 2 and at right angles thereto. As the wing nut 11 is rotated the cam member 12 rotates and draws the jaws closer together as is well understood by one skilled in the art.

The jaws 1 and 2 are comprised of layers 14 and 15 of felt or other suitable material, wood members 16 and 17, rubber strips 18 and 19 and metal strips 20 and 21 all of which are secured together in any suitable manner to form a unitary structure. Integrally formed with the member 20 and at right angles thereto is a U-shaped supporting member 23 which, with the portions 13 and 8, form supporting means for a coil rod CR (Fig. 6) as will be hereinafter explained. A spring pawl member 22 having a hook formed in its upper end is secured to the member 20 and is provided with a portion 56 for releasing it.

A stationary comb member 24 is secured on the upper jaw 1 by means of pins 25 or in any other desirable manner and has its teeth 26 turned to the right and slightly raised above the upper face of the jaw 1 as shown in Fig. 2. A movable comb member 27 having its teeth pointing to the left is held in position on the lower jaw 2 by pins 28 which are located in oblique elongated slots 29 formed in the comb member 27. This manner of supporting the comb member 27 permits the same to be slid upwardly and to the left, referring to Fig. 1, to permit the comb teeth 30 to slide under the raised teeth 26 of the stationary comb member 24. A hook 31 engages an upturned portion 32 and locks the movable comb member 27 in its operated position.

An apron 33 preferably formed of canvas or like material is coiled upon a spring controlled roller 34 which is detachably secured in a depressed portion of the upper jaw 1 as shown in Fig. 2. The canvas apron 33 extends through a slot 36 formed in the metal portion 20 of the upper jaw 1 and may be pulled to be unrolled from the roller 34. A heat insulating member may also be provided over the apron 33. As the roller 34 is under spring tension it tends to pull the apron 33 into the slot 36 and wind the same upon the roller 34 so to prevent the end of the canvas from entering the slot 36 a clip which is too large to pass through the slot 36 may be secured to the end of the canvas.

The coil rod CR may be either hollow or solid and is provided with a pair of knurled knobs 37 and 38, a pair of depressed portions 39 and 40, a ratchet portion 41 and a slot 57 which is adapted to receive the clip secured to the end of the apron 33 to hold the same

in position. The central portion 42 of the rod CR is preferably of smaller diameter than the ends of the rod CR. A spring member 43 shaped to fit the contour of the rod CR is pivoted thereto in any suitable manner at 44 and fits over the slot 57.

Having described the apparatus of my invention I will next describe the manner in which the same is used in permanently waving hair. A small bunch of hair is selected and placed between the jaws 1 and 2 of the clamping member CM. The felt pads 14 and 15 located on the bottom of the jaws rest against the scalp. The fastening member 5, which is in an upright position as shown in Fig. 5 when the jaws are open, is placed in position as shown in Fig. 1 and the wing nut 11 is rotated which due to the action of the cam 12 draws the jaws closer together as before explained to securely hold the hair. The hair passes between the teeth 26 of the stationary comb member 24 and the movable comb member 27 is moved to its operated position and the hook 31 is engaged with the upright member 32 to hold the comb 27 in position. As the teeth 30 of the movable comb 27 engage the hair held between the jaws 1 and 2 they force the hair to the left a sufficient distance to cause the formation of a wave which matches in position with and is similar in duration to the other waves formed. As the felt pads 14 and 15 rest against the scalp it will be seen that this first wave will be formed the thickness of the clamping member from the scalp depending upon the thickness of the jaws 1 and 2.

Next the operator applies a chemical solution to the hair and places the hair at the point where it is desired to have the last wave in position on the coil rod CR. The canvas apron 33 is unrolled from the roller 34 until it reaches the length desired. The end of the apron 33 is also held on the coil rod CR and the spring member 43 is clamped down on it. Then the operator rolls the rod CR toward the scalp at the same time stretching the hair and placing the shorter hairs on the rod CR and under the canvas apron 33 by means of a pin member (not shown) as is well understood in the art. The apron 33 exerts a binding influence upon the hair already placed upon the rod CR and prevents the same from loosening or sliding which is the greatest objection to the method now in use.

After the hair has been wound upon the rod CR the rod CR is placed upon the clamping member CM so that the depressed portion 40 fits within the extensions of the supporting member 23 and the depressed portion 39 fits between the upright member on the jaw 1 and the portion 8 of the fastening member 5. When in this position the spring pawl member 22 engages the teeth of the ratchet 41 which prevents the rod CR from

turning and releasing the hair. The operator next rotates the rod CR by grasping the knurled knobs 37 and 38. An added rotation of the rod CR may be obtained by inserting the end of the pin member above referred to into the end of the rod CR and turning the same. The end of the pin member is of a size and shape to fit within the sunken portion 60 shown in dotted lines in Fig. 6 and acts as a wrench in turning the coil rod CR. The spring pawl 22 engages the teeth of the ratchet 41 and prevents the release of the hair on the rod.

A specially prepared pad shown in Fig. 7 of the drawing is provided and consists of a sheet of tinfoil 53 and a sheet of paper 52 which are provided with a plurality of holes 54, a sheet of oiled flannel 51 which is of double thickness for a portion of its length and a sheet of parchment or vegetable paper 50. These sheets are secured together at one end in any suitable manner and comprise the pad customarily used in the art at this time. The flannel sheet 51 of my pad is of double thickness for a portion of its length to protect the canvas apron 33 from the heater element during the steaming process.

I also provide a pair of flexible metal strips 55 which are secured to the pad in any desired manner. These strips are flexible enough to be bent easily and rigid enough to remain in any position in which they are placed. This specially prepared pad is placed over the coil of hair and the strips 55 are bent by the fingers of the operator in such a manner that they clamp the pad in position on the hair. This eliminates the necessity of the operator holding the pad in position while the heater is being placed in position over the pad.

Before the specially prepared pad is placed over the coil of hair it is saturated with a chemical solution after which a heater which may be of any improved type is placed over the pad. As the heat becomes more intense steam is formed which reacts upon the structure of the hair to cause the formation of a wave. In the method at present in use it is necessary that the heat be stopped at exactly the right moment as to turn it off too soon will prevent the completion of the wave and to leave it on a fraction of a minute more will cause the hair to be injured. With my invention it is not necessary to be so careful with the application of the heat as the canvas apron retains the moisture a longer time and prevents the hair from being injured if the heat is on a reasonable length of time longer than is necessary to complete the waving process.

While I have described my invention in certain particular embodiments, I desire that it be understood that modifications and alterations may be made and that I intend no limitations upon my invention other than

those imposed by the scope of the appended claims.

Having described my invention, what I claim as new and desire to secure by United States Letters Patent is:

1. A hair waving apparatus of the character described, including a clamp comprising a pair of jaw members pivoted at one end, means for fastening the other ends of said members together, a comb secured to one of said jaws and a movable comb located on the other of said jaws. 70 75

2. A hair waving apparatus of the character described including a clamp comprising a pair of jaw members pivoted at one end, 80 means for fastening the other ends of said jaws together, a comb secured to one of said jaws, a movable comb secured to the other of said jaws and means for maintaining said comb in its operated position. 85

3. A hair waving apparatus of the character described including a clamp comprising a pair of jaw members pivoted at one end, means for fastening the other ends of said jaws together, a spring controlled roller secured to one of said jaws and an apron member held on said roller. 90

4. A hair waving apparatus including a clamping member comprising a pair of jaws pivoted together at one end, means for fastening the other ends of said jaws together, a roller carried by one of said jaws, an apron carried by said roller and a pair of combs carried by said jaws. 95

5. A hair waving apparatus including a 100 clamping member comprising a pair of jaws pivoted together at one end, means for fastening said jaws together at their other ends, a roller carried by one of said jaws, an apron carried by said roller, a comb carried by one of said jaws and movable comb carried by said other jaw. 105

6. A hair waving apparatus including a clamping member having a pair of jaws, a roller carried by one of said jaws, an 110 apron carried by said roller, a comb secured to said one of said jaws and a movable comb secured to the other of said jaws.

7. A hair waving apparatus including a clamping member having a pair of jaws pivoted at one end, means for fastening said jaws together at their other ends, a roller carried by one of said jaws, and an apron carried by said roller. 115

8. A hair waving apparatus of the character described including a clamping member comprising a pair of jaws, extending supporting members secured on said jaws, a coil rod having a pair of depressed portions adapted to fit in said supporting members, 120 and a pair of comb members secured on said jaws. 125

9. A hair waving apparatus of the character described including a clamping member comprising a pair of jaws, extending 125 130

supporting members secured on said jaws, a coil rod having a pair of depressed portions adapted to fit in said supporting members, a comb secured to one of said jaws and a movable comb secured to the other of said jaws.

10. A hair waving apparatus of the character described including a clamping member comprising a pair of jaws, a roller carried by one of said jaws and a canvas apron carried by said roller.

11. A hair waving apparatus of the character described including a clamp comprising a pair of jaw members, a spring controlled roller member detachably secured to one of said jaws and an apron member supported by said roller.

12. A hair waving apparatus of the character described including a clamp comprising a pair of jaws, extending supporting members secured on said jaws, a coil rod having a pair of depressed portions adapted to fit in said supporting members, an apron supported on one of said jaws, a clip member on said apron, a slot in said coil rod adapted to receive said clip.

13. The combination with a hair waving apparatus of the character described of a pad having a flexible clamping member secured thereto.

14. A hair waving apparatus including a clamping member, a rod for receiving a coil of hair, a pad adapted to fit over said coil of hair and flexible clamping means for maintaining said pad over said hair.

15. A hair waving apparatus of the character described including a clamping member comprising a pair of jaws, a roller carried by one of said jaws and an apron carried by said roller.

Signed by me at Glen Ellyn, in the county of Du Page and State of Illinois, this 31 day of July, 1931.

GEORGE W. MILLER.
